United States Patent Office.

ALFRED B. COUCH, OF WORCESTER, MASSACHUSETTS.

Letters Patent No. 103,021, dated May 17, 1870.

IMPROVED SHAPING-MACHINE.

The Schedule referred to in these Letters Patent and making part of the same

To all whom it may concern:

Be it known that I, ALFRED B. COUCH, of the city and county of Worcester and Commonwealth of Massachusetts, have invented certain new and useful Improvements in Shaping-Machines; and I do hereby declare that the following is a full, clear, and exact description of the same, reference being had to the accompanying drawings forming a part of this specification, in which—

Figure 1 represents a plan view of such parts of a shaping-machine as are necessary to illustrate my improvement;

Figure 2 represents a side view of the same; and Figure 3 represents a central longitudinal section of the same, on line A, B, fig. 1.

To enable those skilled in the art to which my invention belongs to make and use the same, I will proceed to describe it more in detail:

My improvement relates to that class of machines used for planing metals, known as "shaping-machines," in which the cutting-tool is carried at the extremity of a sliding bar that receives a reciprocating horizontal motion through a crank and connecting-rod.

As shaping-machines have hitherto been constructed, the direction of motion of the sliding bar which carries the cutting-tool has been fixed, and incapable of being varied from that of a line at right angles from the bed or frame of the machine.

The object of my improvement is to provide a means by which the guides which carry the sliding bar may be turned in any direction around an axis on a horizontal plane, without impairing the rigidity of the machine or interfering with any of its other movements.

In the drawings—

The part marked A is the bed, and B the shoe or saddle, fitted to slide upon the bed A in the usual manner.

Upon the shoe B is arranged the guide C, in which moves the sliding bar D, that carries the cutting-tool E, the latter being secured to the head a of the sliding bar D in the ordinary manner, with the hinge-joint b.

The guide C is provided with a circular disk, C¹, at its lower part, which rests upon the saddle B, and a projection, C², is cast upon the under side of said disk C¹, at its central part, which is accurately turned and fitted to a hole truly bored in the body of the saddle B, thereby forming a center or pintle upon which the guide-piece C may be turned as desired, to change the direction of the slide-bar D and cutting-tool E.

The guide C can be secured in any adjusted position by means of bolts F, the heads of which are arranged in a flanged annular groove, G, formed in the saddle B, while their points project upward through

the disk C¹, and are provided with nuts, as shown in the drawings. The screw and its attachments, by which the saddle B is moved to different positions upon the bed A, are arranged in the ordinary manner, and they, being familiar to all machinists, need not be further described.

A shaft, H, having its bearings in the ends of the bed-frame, and receiving motion from any suitable power, drives, by means of a spline, a bevel-pinion, I, the hub of which is prolonged and supported in a bearing, J, which projects downward from the under side of the saddle B.

A flange, e, is formed at the back end of the hub, so that, when the saddle B is moved to the right or left, the pinion I is caused to slide along the shaft H, thereby retaining said pinion at all times in correct relative position in regard to the beveled gear K, into which the pinion I meshes.

The bevel-gear K is secured to the lower end of a short vertical shaft, L, which is arranged through the center of the projection C² and disk C¹, and is provided at its upper end with a beveled pinion, M, which latter meshes into and operates a beveled gear, N, at the side of the guide-piece C. An opening is formed in the guide-piece C to allow sufficient space for the pinion M.

A bushing, O, is arranged through the vertical part of the guide-piece C, and rigidly secured thereto by its flange, n, while a projecting portion of said bushing is fitted to form a bearing for the gear N, as indicated in fig. 3.

A crank-shaft, P, is arranged through and has its bearing in the bushing O, but not concentric to the gear N, as will be seen by referring to the drawings, the center of the crank-shaft P being placed somewhat back from the center of the gear N.

The shaft P is provided at one end with a crank, Q, for operating the slide-bar D, to the rear end of which the crank Q is connected by a rod, R.

A slot, S, is formed in the slide-bar D, through which the crank-shaft P passes, as indicated in figs. 2 and 3, thereby bringing the center of the crank in line with the direction of motion of the slide-bar D.

The opposite end of the crank-shaft P is provided with a disk, T, in which is formed a radial slot, as indicated by dotted lines. The disk T is secured firmly to the shaft P, just outside of the gear N, and a pin, V, projecting from the side of gear N, works in said radial slot, and operates the disk T and crank-shaft P when the machine is in motion.

It will be seen that, when the gear N revolves, carrying with it the disk T, the distance of the pin, V from the center of the crank-shaft P constantly varies throughout the revolution, and the adjustment of the parts is such that the sliding bar D will perform

its outward or cutting movement while the pin V is at its greatest distance from the center of the crank-shaft P, whereby the cutting movement will be made with greater power than the backward or return movement, while the latter will be performed with greater velocity, thereby reducing the times in which the machine is not performing actual service.

From the foregoing description it will be observed that the power communicated to the shaft H will be transmitted to the gear N and parts connected therewith, independently of the position of the saddle B upon the bed A, or of the angular position of the guide-piece C.

The usual position of the axis around which the guide-piece C revolves is vertical, but it may be found convenient for some purposes to construct the machines with the axis in a horizontal or oblique position.

It will be apparent to those skilled in the art that by my improved shaping-machine any piece of metal may be grooved or tongued at various angles, or have its edges planed tapering or oblique, with far greater facility and correctness than can be obtained by taking up and refixing the work for each different angle,

while, at the same time, my machine is capable of performing work with accuracy and precision which is wholly inaccessible to a shaping-machine of ordinary construction.

Having described my improvement in shaping-machines,

What I claim therein as new and of my invention, and desire to secure by Letters Patent, is—

1. The combination with guide-piece C C' C², saddle B, and sliding bar D, of the crank Q and connecting-rod R, substantially as and for the purposes described.

2. The combination with the guide-piece C C' C², saddle B, sliding bar D, crank Q, and connecting-rod R, of the beveled gears I K M N, as shown and described.

3. The combination with guide-piece C C' C² and gears I K M N, of the radially-slotted disk T and eccentrically-arranged crank-shaft P Q, substantially as and for the purposes set forth.

ALFRED B. COUCH.
